UNITED STATES PATENT OFFICE

JAMES C. NUNNALLY, OF GREER, SOUTH CAROLINA

KNOCK-OFF MECHANISM FOR SLUBBERS AND ROVING FRAMES

Application filed March 20, 1930. Serial No. 437,408.

This invention relates to stop motions or knock-off motions of slubbers or kindred machines, as for instance roving frames, fly frames and the like, and particularly to certain improvements upon the construction illustrated in my application for patent filed February 23, 1929, Serial No. 342,142.

As was stated in this prior application, at the present, as far as known to me, all roving frames are doffed by the rack knock-off motion which is shifted or changed each time that the tension gear is adjusted and, therefore, when the yarn or roving gets slack in damp weather or tightens up in dry weather, the operative has to change the tension and these adjustments change the rack-knock-off motion. This change in the rack knock-off motion will affect the yardage of stock on the bobbins, making it impossible to keep the creeling all run out together, thus causing a waste of stock at each creeling.

The general object of the present invention is the same as in my prior application for patent, that is, to avoid the difficulties above referred to and cause the knock-off to occur by the use of mechanism driven directly from the contact shaft of the slubber, which contact shaft in all machines known to me is driven independently of the tension motion and thus doing away with the difficulties due to a changing of the knock-off mechanism each time that the tension is changed and thus giving an even yardage on each doff of the roving, the mechanism operating to shift the belt shipper rod of the frame automatically after a predetermined number of revolutions of the contact shaft.

A further and more particular object of the present invention is to provide a mechanism which will not require the services of an operator in order to secure the knock-off of the slubber, but will do all the work of

knocking off and eliminate any attention by the operator.

A further object is to provide a construction of this character which will not require watching, but merely require that the attendant shall doff when the device knocks off. 50

Other objects will appear in the course of the following description.

My invention is illustrated in the accompanying drawings, wherein:— 55

Figure 1 is a rear elevation of a portion of a slubber or roving frame with my knock-off mechanism applied thereto;

Figure 2 is an elevation of the knock-off lever support, the oscillating arm being in section; 60

Figure 3 is a section on the line 3—3 of Figure 2;

Figure 4 is an elevation of the hook support, the bobbin rail being shown in section; 65

Figure 5 is a section on the line 5—5 of Figure 4;

Figure 6 is a side elevation of the worm wheel and worm, the crank arm being shown in section. 70

Figure 7 is a fragmentary rear elevation as in Figure 1, but showing the parts in position before the rack has been shifted to its initial position in order to doff; 75

Figure 8 is a fragmentary rear elevation showing certain of the parts when the latch has been fully retracted and the knock-off rod fully shifted.

In these drawings I have only illustrated so much of a roving frame, as for instance, a slubber frame, as will be necessary for an understanding of my invention. 80

In these drawings, 10 designates the usual roll beam and 11 the sampsons supporting the same. The shipper rod is designated 12 and is operatively connected to a knock-off arm or lever 13 of the usual character pivoted at 14 upon the roll beam 10 and extended longitudinally as at 15 and then downward, 85 90

this portion of the arm being of such weight that as soon as this end of the arm is unsupported, it will drop and knock off the frame. The top cone is designated 16 and is driven as usual from twist gear train, the belt 18 being shiftable over the faces of the cones 16 and 17 to change the speed by means of the usual rack 19 actuated in the usual manner by mechanism which it is not necessary to show as it is well known. The contact shaft 20 as usual carries the mutilated beveled gear wheel 21 engaging the beveled gear wheel 22 on top cone shaft 23 so that thus the contact shaft receives its motion from the top cone shaft which in turn receives its motion from the twist train driven in the usual manner. So far I have described elements which are commonly found in all slubbers, roving machines and fly frames. Mounted upon the contact shaft for rotation therewith is an extension shaft 24 carrying at its upper end the beveled gear wheel 25 and mounted in supports 26 is a shaft 27 carrying upon it the gear 25a and worm 28. One of the supports 26 has a bracket 29 carrying the worm wheel 30. Loosely mounted upon the shaft 30a of the worm wheel is the crank arm 31 having the crank pin 32. Carried by the pin 32 is the rod 33. One wheel 30 is provided with a laterally projecting pin 34. The crank arm 31 is disposed in the path of movement of this pin. The worm wheel 30 rotates in a counter-clockwise direction. During the rotation of this worm wheel, the pin 34 will engage the arm 31, which is loose upon the shaft 30a, as before stated, when this arm 31 is in a depending position and will carry the arm 31 up in a counter-clockwise direction to a position where the arm 31 extends upward. Upon a further movement of the worm wheel, the arm 31 will be carried up beyond its vertical position and will then of its own weight swing downward and forward in a counter-clockwise direction of itself, and remain in this position until pin 34 has again picked it up. So far, I have described the construction which is shown in my pending application for patent, Serial No. 342,142, filed February 23, 1929, to which reference has been previously made.

In this prior application, I showed a depending swinging latch which was disposed beneath the knock-off lever 13 and supported the same, this latch being shifted laterally and out of its supporting position by the rod 33. The improved mechanism for this purpose will be now described.

Pivottally mounted upon the rail 10 at 35 is a depending support designated generally 36 designed to normally support the weighted end of the lever 13. This support 36 extends straight downward from the pivot 35, then extends at right angles or rearward to-

ward the back of the slubber or other roving frame, as at 37, and then downward, as at 38, the lower portion of this portion 38 having its outer face slightly curved at 37a. The portion 38 is formed to provide a shoulder 39 and to provide a latch receiving recess or chamber 40 below this shoulder. Disposed within this chamber is a latch 41 which is mounted upon a transverse shaft 42. This shaft extends laterally outward toward the front of the machine and carries upon its end the weighted arm 43.

This arm at one end is enlarged so as to provide a weight 44 and the other end of the arm is formed with a pivotal section 45 pivoted at 46. The rear end of the section 45 is forked to embrace an ear on the extremity of the main section of the arm 43 and the confronting end faces of the main section 43 of the pivoted section 44 are so formed as is obvious from Figure 3, that while the section 45 may readily swing upward, it cannot swing downward beyond a position of alinement with the main section 43. The rod 33 is formed at its extremity with a somewhat elongated loop or eye 47 which surrounds and loosely embraces the shaft 42 so that the rod 33 has longitudinal play before striking the pin 42 which constitutes the shaft upon which the arm 43 and the latch 41 are mounted.

Attached to the usual carriage rail 49 is an angular member 48. This is rigidly engaged with a vertically extending plate 50 notched at its ends as at 50 to straddle and engage with a guide bar on the sampson post 11. The rail 49 is commonly found in slubbers and supports all the bobbin bolsters on which the spindles or bobbins rotate. These bolsters vary in number from fifty-six to one hundred and seventy-six. This rail is traversed up and down by the usual lifting motion on the frame.

Mounted upon the plate 50 is an angular member 52, this angular member having a slot 53 through which it is bolted as at 54 to plate 50. The opposite end of this angular member carries a bolt 55 which passes through a slot 56 in an extension piece 57 which at its upper end is formed with a hook 58. It is this hook that is adapted to engage over the finger 45 at the extremity of the arm 43.

It will be obvious that this member composed of the sections 52 and 57 is adjustable. When the carriage or rail 49 moves downward to permit the bobbins to be doffed, the hook 58 will engage with arm 43 and will draw the forward end of the arm downward against the weight 44, thereby rotating latch 41 from a projected position to a retracted position. The provision of the slots in the sections 52 and 57 permits the hook 58 to be shifted toward or from the rear of the slubber to make it properly en-

gage with the knuckle end of the arm 43. The slot 56 is particularly designed to make it possible to adjust this hook 58 to suit the length of bobbins which may be $11\frac{1}{2}$, $9\frac{1}{2}$ 5 and $8\frac{1}{2}$ inches in length. In my prior construction, described in my application, Serial No. 342,142, filed on the 23rd day of February, 1929, the knock-off occurred at the lower end of bobbins where it was not possible 10 to doff the frame as the operative had to run the frame half way of its traverse in order to doff. Now with my present construction, the knock-off lever 15 drops on to the face of the latch at the change of traverse and holds the weight until half of 15 the length of the bobbins has been made whereupon the latch is rotated out from beneath the knock-off arm 15 or lever, thus stopping the frame at the proper doffing 20 place of bobbin, making all doffs the same.

It is to be understood and as described in my prior application, that the contact shaft 20 and the bevel gear 25 will make a large number of revolutions before the worm 25 gear 30 will have made one complete revolution. As the worm gear 30 starts its revolutions at the beginning of the bobbin filling operation, the arm 31 will be in a depending position, and when the pin 34 30 strikes the arm 31 in the rotation of the worm wheel, the arm 31 will be retracted or moved toward the right in Figure 1 and then after the arm 31 has reached its horizontal position and is moving upward and 35 laterally toward the left, the rod 33 will be shifted forward.

This forward movement of the rod 33 will not affect the swinging support 36 until the arm 33 has moved a distance equal to the 40 length of the slot in the eye 47. Generally speaking, when the worm wheel 30 has made a complete revolution, the rod 33 will be forced outward and the support 36 will release, as will be later described in detail, 45 the knock-off lever 13, causing the knock-off arm or lever to descend, shifting the shipper toward the right in Figure 1 and stopping the machine for doffing. Of course, it will be understood that the contact shaft 20 50 makes a predetermined number of half revolutions during the filling of the bobbins and before the doffing thereof, as for instance, seventy-two half revolutions or thirty-six full revolutions for $11 \times 5\frac{1}{2}$ slubbers while 55 for intermediate frames, the contact shaft makes seventy-two half revolutions or thirty-six complete revolutions to one revolution of the worm gear 30.

The pin 34 acts to swing this arm 31 over its center and at this time, the end of the eye 47 strikes the pin 42 and swings the support 36 just enough to permit the lower end 60 of the lever 13 to drop from the shoulder 39 upon which the end of this lever 13 initially

rested on to the upper face of the latch 41, as shown in Figure 1.

The swinging of the supporting arm 36 toward the left in Figure 1 will swing the left hand end of the member 45 into a position beneath the hook 58. Upon a downward movement of the hook 58 caused by the last downward movement of the rod, the arm 43 will be turned in a counter-clockwise direction which will turn the latch 41 in a counter-clockwise direction, releasing the lower end of the arm 13 and allowing this arm, therefore, to drop the full distance necessary to knock off the loom.

When the frame is doffed, the heavy end 44 of the arm 43 swings the latch 41 back into position for the next doff. The purpose of the knuckle or pivoted section 45 is to prevent any trouble when the arm 13 makes the first drop from shoulder 39 on to the upper face of the latch 41. It is to be understood that the loop 47 at the extremity of the rod 33 is to permit the arm 31 to make one complete revolution with the worm gear and yet only move the depending 50 pivoted supporting arm 36 about three-eighths of an inch when it reaches the extremity of the loop. With this construction, the mechanism does all the work of knocking off the roving frame so that the operator 55 does not have to give the frame any attention whatsoever, but the mechanism completes the whole operation of knocking off so that the operator does not have to do anything except doff the bobbins whereas with 60 my old construction, the operator was obliged to watch the machine.

It may be stated with regard to Figure 1 that in the drawings I have shown the arm 31 and the pin 34 as if they were disposed 65 on the rear side of the wheel 30 and the bracket 29 is disposed on the front side of the wheel 30, that is, toward the front of the machine. This has been illustrated in this way to make the operation of the device clear, but as an actual fact, the bracket 29 will extend downward on the rear of the wheel 30 and the arm 31, the pin 34 and the rod 33 will all be disposed on the front side 70 of the wheel 30.

With the mechanism so far as described, the arm 31, when it reaches a horizontal position extending toward the support 36, the inner extremity of the eye 47 will strike the pin 42 and force the pivoted support 36 laterally a distance just sufficient to permit the extremity of the arm 15 to drop from the shoulder 39 on to the latch 41.

Then upon a downward movement of the bobbin rail 49, the latch 41 as previously 80 described will be retracted, allowing the angular end of the lever 15 to drop still further or across the front of the latch. This will prevent the support 36 from swinging 85 toward the right in Figure 1, but if the 90

knock-off lever 15 be lifted by the operator or in other words, if the rod 12 be shifted by the operator toward the left in Figure 1, this will act to lift the arm 15 and as the arm 15 is lifted, the support 36 will swing slightly toward the right so that the shoulder 39 will again engage beneath the knock-off lever 15. In other words, the operator by a very slight movement of the part 12 can again reset the knock-off arm lever 15 immediately after doffing or immediately after the knock-off lever has fallen off the shoulder 39 on to the latch 41. In order to prevent the support 36 from swinging back 15 into a position where the knock-off lever may rest upon the shoulder 39, until the rack 19 is shifted back by the operator to its starting point as is necessary during the doffing operation, I provide a rest designated 59 which is mounted upon the extremity of the rack 19. This rest is mounted upon an angular bracket 60 and the rest is somewhat elongated in the direction of the rod 19.

Mounted upon the connecting rod 33 is a finger 61 which extends outward and downward relative to the connecting rod and when the rack 19 has reached the position at the extreme left of its travel, this rest 59 will be disposed in a position such that when the arm 31 is in a horizontal plane and pointed toward the support 36, the finger 61 will bear upon this rest 59. This supports the arm 31 and rod 33 from any further movement until the rack 19 has been shifted by the operator back to its initial position.

This shifting of the rack carries the rest out from beneath the finger 61 and immediately that this is done, the arm 31 swings down to the position shown in full lines in Figure 1. By means of the rest 59, this rod 33 is prevented from moving downward and toward the right in Figure 1 and hence the inner end of the eye 47 will hold the support 36 swung toward the left in such position that the knock-off lever 15 cannot by any possibility rest upon the shoulder 39. The operator cannot, therefore, hold the weighted knock-off lever 15 up permanently.

He may shift the rod 12 momentarily but as soon as he releases it, the arm 15 will drop down beyond the shoulder 39 and the operator cannot again engage the knock-off lever 13 and the shoulder 39 until he winds the rack back to the starting point for the new doff. Without this means for stopping the downward movement of the arm 31 and the rod 33, the operator could pull back on rod 12 and hold the knock-off mechanism out of operation by engaging the arm 15 with shoulder 39. Thus the bobbins would continue to run and fill beyond the allotted amount. This is entirely prevented by the mechanism which I have disclosed.

63 I claim:—

1. In a stop motion for winding machines, the winding machine including a vertically reciprocatable bobbin rail, a shipper lever forming part of the stop motion, a swingable member normally supporting the shipper lever in a raised position, a latch carried by the swingable member and normally projecting therefrom, means actuated from the driving mechanism of the winding machine acting after a predetermined time from the 75 start of said driving mechanism to release the direct engagement of the member with the lever and permit the lever to drop upon said latch, and means actuated upon a downward movement of the bobbin rail to retract 80 the latch.

2. In a stop motion for winding machines, the winding machine including a vertically reciprocatable bobbin rail, a gravity actuated shipper lever forming part of the stop motion, a shiftable member normally supporting the shipper member in a raised position, a latch carried by the swingable member and normally projecting therefrom, means actuated from the driving mechanism of the winding machine acting after a predetermined time from the beginning of a winding operation to swing the member in a direction to release the direct engagement of the member with the lever and permit the lever to drop upon said latch, and means actuated upon a downward movement of the bobbin rail, retracting said latch to permit the full descent of the shipper lever, the means then acting to return the latch to its 100 normal position when the bobbin rail is raised.

3. In a stop motion for winding machines, the winding machine including a vertically reciprocatable bobbin rail, a gravity actuated shipper lever, means normally supporting the shipper lever in a raised position, means actuated from the driving mechanism of the winding machine acting after a predetermined time after the start of the mechanism to shift the supporting member to permit an initial slight downward movement of the shipper lever, and means actuated upon a downward movement of the bobbin rail to entirely release said supporting member from the lever to permit the lever to 110 fully drop and stop the machine.

4. In a stop motion for winding machines, the winding machine including a vertically reciprocatable bobbin rail, a vertically movable shipper lever, means normally holding one end of the shipper lever raised, means actuated from the driving mechanism of the winding machine acting after a predetermined length of time from the start of said 125 driving mechanism to partially release the shipper lever, and means then acting upon a downward movement of the bobbin rail to entirely release the shipper lever.

5. In a stop motion for winding machines, 130

the winding machine including a vertically reciprocatable bobbin rail and a contact shaft, a gravity actuated shipper lever, a shiftable support therefor normally supporting the shipper lever in a raised position, a latch carried by the support, means actuated by said contact shaft to swing said member from beneath the lever and permit the lever to drop upon said latch, a shaft upon which the latch is mounted, a counter-weighted lever mounted upon said shaft, a member engaging said lever opposite its counter-weight, and operatively engaged to move with the bobbin rail whereby as said bobbin rail moves downward, the latch will be rotated to release position to release its engagement with the shipper lever and to permit the shipper lever to drop a distance sufficient to cause the knock-off of the machine.

6. In a stop motion for winding machines, the winding machine including a vertically reciprocatable bobbin rail, a shipper lever adapted to move by gravity to a knock-off position, a swingable support having a shoulder upon which the lower end of the shipper lever is supported and carrying a latch normally projected in a position just beneath said shoulder, a shaft mounted on the member and upon which said latch is mounted for oscillation, a counter-weighted lever mounted upon said shaft, a vertically reciprocatable hook-shaped member operatively engaged with the bobbin carrying rail to move therewith, and so disposed with relation to the unweighted end of the lever that when the pivoted supporting member swings toward the hook-shaped member, the free end of the counter-weighted lever will be carried beneath the bill of the hook-shaped member, a rotatable element, a rod connected to the rotatable element to be reciprocated thereby, and having sliding engagement with said shaft for a predetermined distance upon a movement of the rod in one direction and then acting to shift the pivoted member in a direction to release the shipper lever and permit it to drop upon the latch, and means actuated by the driving mechanism of the winding machine acting to completely rotate said rotatable member after a predetermined time from the starting of the driving mechanism.

7. In a winding machine, a vertically reciprocatable bobbin rail, a knock-off lever having a vertically movable portion descending to stop the machine, a pivoted support having a shoulder normally supporting the knock-off lever in a raised position and having a retractable latch disposed immediately below the shoulder, a counter-weighted arm mounted to shift with said latch, the counter-weight of the arm acting to project the latch, said arm when tilted against its counter-weight acting to retract the latch, a ver-

tically reciprocatable member having its extremity normally disposed above the extremity of the arm, said member having operative connection to the bobbin rail of the winding machine to be reciprocated thereby, a contact shaft having a beveled gear thereon, a longitudinally extending shaft driven from the beveled gear and carrying a worm, a worm wheel engaged by said worm, the worm wheel having a laterally projecting pin, an arm loosely mounted upon the shaft of the worm wheel and in the path of motion of said pin, a rod connected to the extremity of said arm and slidably connected to the pivoted support for limited movement in one direction, said rod after said limited movement acting to swing the supporting member to carry its shoulder from beneath the shipper lever to permit the shipper lever to drop upon the latch. 85

8. In a stop motion for winding machines, the winding machine including a vertically reciprocatable bobbin rail, a shipper lever forming part of the stop motion, and a belt shifting rack, a swingable member normally supporting the shipper lever in a raised position, a latch carried by the swingable member and normally projecting therefrom, means actuated from the driving mechanism of the winding machine acting after a predetermined length of time from the start of said driving mechanism to release the direct engagement of the member with the lever and permit the lever to drop upon said latch, means actuated upon the downward movement of the bobbin rail to retract the latch to permit the full descent of the shipper lever, and means carried by the rack preventing the swingable member from moving back into a position where it can engage said shipper lever when the latter is raised until the rack has been shifted to its initial position. 100

9. In a winding mechanism, a vertically reciprocatable bobbin rail, a belt shifting rack, a knock-off lever having a vertically movable portion acting to stop the machine when its descends, a support pivoted at its upper end and having a shoulder normally supporting the knock-off lever in a raised position, a contact shaft having a beveled gear thereon, a longitudinally extending shaft driven from the beveled gear and carrying a worm, a worm wheel engaged by said worm, the worm wheel having a laterally projecting pin, an arm loosely mounted upon the shaft of the worm wheel and in the path of motion of said pin, a rod connected to the extremity of said arm and having an eye slidably connected to the pivoted support for limited movement in one direction, said rod after said limited movement acting to swing the supporting member to carry its shoulder from beneath the shipper lever to permit the shipper lever to drop upon the latch, and means preventing a 136

movement of said rod in a direction away from the pivoted support until the rack is shifted to its initial position comprising a finger mounted upon the rod and a supporting member for said finger mounted upon the rack and disposed in the path of downward movement of said finger until the rack has been shifted a distance toward its initial position.

5 10 In testimony whereof I hereunto affix my signature.
